DIAMETRICALLY COOPERATING VANE
PUMPJoseph R. Richer, Cleveland, Ohio; Ella Richer
Administratrix of Joseph R. Richer, deceased

Application October 15, 1945, Serial No. 622,433

1 Claim. (Cl. 103—138)

1

The invention relates to rotary pumps and more particularly to vane type pumps.

One object of the invention is to provide a novel vane type pump characterized particularly by its high efficiency, freedom from wear, and the overall simplicity of its construction.

Another object is to provide an improved vane type pump adapted to deliver a smooth, substantially uniform flow of fluid with a minimum of pulsations.

Another object is to provide a vane type pump having novel means for accurately locating the vanes with respect to the walls of the pump chamber so as to minimize slippage or internal leakage and at the same time reduce the wear on the vanes and chamber walls to a minimum.

Another object is to provide a rotor for vane pumps embodying novel features of construction which greatly facilitate the manufacture of the rotor and which effectually prevent distortion of the same in use.

Still another object is to provide a rotary pump constructed in a novel manner to facilitate adjustment of the rotor bearings to compensate for wear.

Other objects and advantages of the invention will become apparent from the following detailed description of the preferred embodiment illustrated in the accompanying drawings in which:

Figure 1 is an end elevational view of the improved pump with one end section of the housing removed and with some parts broken away.

Fig. 2 is a longitudinal sectional view of the pump taken in a vertical plane substantially on the line 2—2 of Fig. 1.

Fig. 3 is a perspective view of one of the rotor vanes.

Fig. 4 is a diagrammatic view showing the form of the pump chamber.

Fig. 5 is a diagrammatic view similar to Fig. 4 but showing the rotor in a different angular position.

Referring to Figs. 1 and 2 of the drawings, the pump selected to illustrate the invention comprises a housing 10 forming a compartment for an annular member or barrel 11 defining a generally cylindrical pump chamber and a rotor 12 carrying a plurality of radially projecting blades or vanes 13 adapted to cooperate with the walls of the pump chamber. The housing 10 is preferably constructed of a plurality of sections including a hollow, generally cylindrical central section or body 15 having end sections 16 and 17 secured to opposite ends as by bolts 14. Openings 18 and 19 at opposite

2

sides of the body 15 may be used interchangeably as fluid inlet and outlet ports depending upon the direction of rotation of the rotor 12.

The rotor 12 comprises a cylindrical body 20 provided at opposite ends with shaft extensions 21 and 22 by which it is rotatably supported in end sections 16 and 17 of the housing. In the exemplary pump, the shaft portion 21 is formed integrally with the body 20 of the rotor and is extended through the end section 16 as at 21' to provide for attachment of a driving gear or pulley. The shaft 22 is preferably removably secured to the body of the rotor as by screws 23 projecting through a flange 24 integral with the shaft.

As will be seen by reference to Fig. 2 of the drawings, the body 20 of the rotor is substantially longer than the barrel 11 forming the pump chamber and extends therethrough to seat 20 in recesses 25 and 26 in the end members 16 and 17. The end member 16 is formed with a hub-like extension 27 axially aligned with the recess 25 and provided with a counterbore forming a seat for a roller bearing 28 in which the shaft 21 is journaled. A nut 29 threaded on the shaft and arranged to bear against the outer end of the bearing race ring provides for adjustment of the shaft axially of the bearing. Preferably, the bearing 28 is held in its seat by a retaining ring 30 and a cap 31 removably secured to the outer face of the end member 16 as by machine screws 32. Suitable glands or packing rings 33 and 34 arranged on opposite sides of the bearing prevent leakage of lubricant around the shaft.

In the particular pump construction illustrated, the hub portion of the end member 16 is formed with radially projecting ears 35 for mounting the pump on a machine frame or other suitable support. The ears are apertured as at 36 for the accommodation of bolts by which the pump is removably attached to its support.

The end member 17 of the housing is generally similar to the companion end member, having a hub portion 37 counterbored to provide a seat for a roller bearing 38 in which the shaft 22 is journaled. A flanged retaining member 39 secured to the end of the shaft 22 as by a screw 40 retains the shaft and bearing in assembled relation. A cap 41 removably secured to the end section 17 protects the bearing and, in conjunction with a gland or packing ring 42, serves to retain the lubricant in the bearing recess.

In the exemplary pump, the rotor 12 is equipped with a pair of the vanes 13 disposed at right

angles to each other. The vanes may be alike and, as shown in Fig. 3, each consists of a flat, generally rectangular sheet metal plate formed with a central notch 45 of a depth equal to one-half the width of the plate to permit them to be interfitted in crossed relation. In practice, the vanes are dimensioned crosswise so as to fit snugly between the end members 16 and 17 of the pump while the lengthwise dimensions are such as to enable the vanes to coat with diametrically opposite walls of the pump chamber defined by the barrel 11.

To accommodate the rotor blades, the body 20 of the rotor is formed with transverse slots 46 opening in the end to which the shaft 22 is secured. The slots 46 are dimensioned to receive the vanes with a sliding fit and are preferably of a slightly greater depth than the width of the vanes to permit adjustment of the pump body axially of the pump chamber to take up the wear on the rotor bearings.

By reason of the novel means provided for preventing warping, the rotor body may be hardened after the slots 46 are formed and thereafter ground to exact dimensions. For this purpose, the rotor body 20 is formed at one end with an axially projecting pad 47 having a relatively shallow cylindrical recess 48 adapted to receive a cylindrical plug 49. After the slots 46 are cut on the rotor body, the plug 49 is inserted in the recess and acts to prevent the slotted end of the body from warping during the hardening process. The plug, of course, is removed for the insertion of the blades 13 and is reinserted in its recess after assembly of the blades with the rotor.

Distortion of the rotor during the operation of the pump is effectually prevented by forming the flange 24 of the shaft 22 with a recess 50 adapted to receive the pad 47 with a relatively snug fit. Thus when the rotor parts are assembled, the slotted sections of the rotor body are locked between the plug 49 and the walls of the recess 50 and effectually held against movement radially of the rotor body.

As indicated above, the working chamber of the pump is defined by the barrel 11 which is readily replaceable in case it becomes worn in use. Referring to Figs. 1 and 2 of the drawings, the barrel 11 as herein shown comprises a generally cylindrical casting having radially projecting flanges 51 and 52 at opposite sides. The flanges are dimensioned to provide a tight sliding fit in recesses 53 and 54 formed in the inner walls of the central section 15 of the housing midway between the ports 18 and 19. The flanges and the barrel 11 thus divide the interior of the housing into two separate compartments 55 and 56 associated respectively with the ports 19 and 18 and communicating with opposite sides of the pump chamber through ports 57 and 58 formed in the peripheral walls of the barrel. Set screws 59 threaded into the housing 15 and bearing against the flanges 51 and 52 provide means whereby the barrel may be adjusted transversely of the rotor axis to take up any wear which may occur on extended use.

As will be seen by reference to Fig. 1 of the drawings, the barrel 11 is mounted in the housing 10 so that the rotor 12 is disposed eccentrically therein. More specifically, the barrel is mounted so that the rotor is substantially in contact with the inner wall at the upper end of the barrel and spaced from the wall at the lower end of the barrel. This space forms a

channel 60 through which fluid is carried between the ports 57 and 58 by the vanes 13 as will appear presently.

The inner peripheral wall of the barrel 11 is shaped in a novel manner to enable the pump to deliver a smooth uniform flow of fluid substantially without pulsations. As shown in Figs. 4 and 5, a section A of the wall in the upper part of the pump chamber is formed on a radius R substantially equal to the radius of the rotor and having its center C coaxial with the rotor. The section A extends through an arc of approximately 90 degrees and corresponds to the spacing of adjacent vanes 13.

15 Diametrically opposite the section A, the pump chamber walls are formed with a section B having a radius R_1 having the same center C as the radius R but longer by an amount corresponding to the difference between the length of the vane 20 13 and the diameter of the rotor 12. Thus, the surfaces A and B are spaced apart substantially the length of a vane so that the opposite ends of the vane may coat therewith. The section B extends through an arc slightly greater than 90 degrees, preferably by an amount substantially equal to the thickness of one of the vanes 13.

20 The wall sections A and B are joined by arcuate wall sections D and E containing the ports 57 and 58. These wall sections are formed on radii R_2 and R_3 of equal length but having their respective centers C_1 and C_2 located below and in lateral spaced relation to the center C of the rotor. It has been found that the accurate formation of the surfaces of the sections D and E is 25 facilitated and maximum efficiency is obtained by locating the centers C_1 and C_2 on axes x and y passing through the center C and disposed at angles of 45 degrees to a line z connecting the mid-points of the wall sections A and B. By reason of their circular form, the several wall surfaces of the pump chamber may be finished with a high degree of precision by simple grinding operations.

30 The particular shape and location of the wall sections D and E are also advantageous in shifting the vanes 13 transversely of the rotor as they pass from the channel 60 of the pump chamber defined by the rotor and the wall section B to the opposite wall section A. Wall section D performs 35 that function when the rotor turns clockwise as viewed in Fig. 4 while wall section E shifts the vanes upon reverse rotation of the rotor. It will be evident that in the first instance, port 58 serves as the inlet and port 57 as the outlet, while in the 40 second instance the functions of the ports are reversed. In either case, the shifting of the vane is timed so as to close the inlet end of the channel before the outlet end is opened by the passage of the companion vane from the wall section B. 45 Slippage or internal leakage between the inlet and outlet ports is thus avoided.

50 Leakage between the vanes and the wall section B is reduced to a minimum and wear on the vanes and on the chamber wall is reduced to a 55 minimum by the novel arrangement provided for confining the radial projection of the vanes within accurately defined limits. For this purpose, the slots 45 in the vanes are formed with a width such that the ends of the vanes just clear the 60 surface of the wall section B when the edge of the slot of one vane engages the side of the companion vane. Each vane therefore acts as a positive stop for the companion vane and accurately determines the limit position when projected radially from the rotor.

The operation of the improved pump will be readily apparent from the foregoing description. Assuming that the rotor is driven in a clockwise direction as viewed in Fig. 4, fluid is admitted through the inlet ports 19 and 58 at the right side of the pump to the inlet section of the pump chamber defined by the wall section E. As the projecting end of the vane moving along the wall section D approaches the section A, the vane is shifted across the rotor into close proximity to the right edge of the wall section B thus closing the inlet end of the channel 60.

While the foregoing is occurring, the companion vane is moving along the wall section B to force out the charge of fluid previously received as that vane passed the inlet port. The fluid entrapped between the two vanes is carried along the channel to be discharged at the outlet port when the leading vane passes from the wall section B. Thus the vanes act alternately to draw fluid through the inlet port and carry it through the channel 60 of the pump chamber to the outlet port. Leakage between the ports is effectually prevented since the inlet end of the channel 60 is closed before the outlet end is opened for the discharge of fluid. Moreover, as the leading vane passes from the wall section B to the wall section D, the chamber is opened gradually to the outlet port to permit a smooth, pulsationless discharge of fluid through the port.

The operation of the pump is substantially the same upon rotation of the rotor 12 in the opposite direction. Under such conditions, fluid is drawn in through the ports 18 and 57 and discharged through the ports 19 and 58. The wall section E instead of section D acts to shift the rotor vanes as described above.

It will be apparent from the foregoing that the invention provides a vane type pump of novel and improved construction. Uniform, substantially pulsationless fluid delivery is obtained through the novel shaping of the walls of the pump chamber. The shaping of the chamber walls is also instrumental in reducing slippage or internal leakage in the pump. The improved arrangement for limiting the movements of the vanes enables them to function with maximum efficiency while reducing wear on the critical parts

of the pump structure. In general the improved pump is characterized by its simplicity of construction which greatly facilitates manufacture and assembly of the parts and which materially reduces its cost.

I claim as my invention:

In a pump, in combination, a barrel forming a pump chamber having inlet and outlet ports at opposite sides, said chamber having arcuate wall sections between said ports formed on a common center, one of said wall sections having a greater radius than the other section, a cylindrical rotor mounted in said chamber with its rotational axis coincident with the common center of said wall sections, said rotor having a pair of transverse slots disposed at right angles to each other and intersecting at the axis of the rotor, a vane mounted in each slot for endwise sliding movement across said rotor, said vanes having cooperating notches at their point of intersection of a depth equal to one half the width of the vane to allow the vanes to slide relative to each other, the widths of said notches being such that each vane is operative to block the other vane and maintain the end of the other vane in spaced relation to said one wall section during its passage thereover.

JOSEPH R. RICHER.
